for the improvement in the manufacture of elastic garter tops and stockings, and particularly for the manufacture of elastic garter tops and stockings in which the elastic is incorporated with inelastic yarn or yarns to impart elasticity to the fabric and to simulate a rib appearance.

UNITED STATES PATENT OFFICE

Patent No. 2,313,332
Issued March 9, 1943
For an improvement in the manufacture of elastic garter tops and stockings, and particularly for the manufacture of elastic garter tops and stockings in which the elastic is incorporated with inelastic yarn or yarns to impart elasticity to the fabric and to simulate a rib appearance.

2,313,332
KNITTED FABRIC

Oscar Fregeolle, Central Falls, R. I., assignor to the Hemphill Company, Central Falls, R. I., a corporation of Massachusetts
Application June 4, 1941, Serial No. 396,500
(Cl. 66—172)

8 Claims.

This case deals with certain improvements in stocking tops, more especially, elastic garter tops in which an elastic yarn is incorporated with inelastic yarn or yarns to impart elasticity to the fabric and to simulate a rib appearance.

In the figures of drawing:

Fig. 1 is a conventional showing of a section of fabric greatly enlarged and illustrating one embodiment of the invention.

Fig. 2 is an elevation of part of an article of hosiery to which the invention has been applied.

Referring to Fig. 1, elastic yarn such as Lastex has been incorporated with an inelastic yarn at and adjacent the selvage of the fabric and under sufficient tension so that when released and allowed to contract, the said elastic yarn will draw together sufficiently to cause the fabric to assume a rib-like appearance. One specific embodiment of the invention involves knitting the elastic yarn as herein illustrated at spaced wales and independently in those wales, but it is to be understood that other schemes may be employed, for example, the elastic yarn may be knitted in conjunction with an inelastic yarn, may be laid in a base fabric of inelastic yarn or incorporated to be held at spaced wales in any other satisfactory way.

According to the principle of the invention, for several courses at and adjacent the selvage, inelastic yarn employed is to be finer or of less weight than a yarn substituted after those first few courses, so that the edge of the fabric will be drawn inwardly as illustrated in Fig. 2. This desired result is to be obtained by feeding a single inelastic yarn of finer gage than would normally be employed for the particular gage of needle knitting, or than would be employed for a particular stocking top under normal procedure. Then after the first few courses, that is, enough courses to get a sufficient drawing in of the fabric at the edge, a yarn change is to be made to a heavier inelastic yarn, preferably a yarn such as would normally be knitted when considering the gage of needles and type of fabric being produced. The above may be varied by continuing to feed the relatively light inelastic yarn after the first few courses and feeding a second yarn with it so that the net effect will be that of fabric in which, at the first few courses, a relatively light inelastic yarn is knitted and wherein a change is made to a yarn or yarns considerably heavier.

Elastic yarn 1 is first introduced to be taken by every other needle for forming a selvage and that yarn may be taken a single time as herein illustrated or needles may be "loaded up" so that a selvage is produced in which several strands

of elastic are incorporated at the first course. Then the relatively light inelastic yarn 2 is fed to all needles, but for several courses, it is, according to the preferred embodiment of the invention, tucked at wales intermediate those wales in which the elastic is knitted or otherwise incorporated to be held. In the particular illustration herein used by way of example elastic is taken in what will be called alternate wales 3, 5, 7, 9 and 10 11. The intermediate wales are to be designated as 4, 6, 8 and 10. The elastic yarn is fed continuously according to the knitting illustrated in Fig. 1 and while the first course of elastic will, when contracted, merely constitute a selvage as it straightens out and threads itself through each of the initial sinker wales in course A, the said elastic yarn will thereafter be drawn into independent knitted stitches as in course B. Of course, it contracts since it is knitted under suitable tension to draw the fabric together sufficiently for presenting a rib appearance and for imparting proper elasticity to the garter top as a whole.

The inelastic yarn 2 is tucked at the wales 4, 6, 8 and 10 and while these tuck stitches may include any number of accumulated stitches, it has been found quite satisfactory to accumulate two loops, for example, the loops drawn on intermediate needles at courses A and C. These are cast off when the next course of inelastic yarn E is drawn. Elastic yarn had been knitted again at the course D prior to the drawing of inelastic yarn at course E. Another elastic yarn course F is knitted whereupon course G of inelastic yarn completes another tuck cycle. Courses A and C make up one tuck group while courses E and G make up a second tuck group. This is continued throughout any desired distance at the top of the stocking and it has been found that about six tuck groups serves very satisfactorily, although that may be varied, depending upon the gage of the material being knitted and the type of top under consideration.

At course H a heavier inelastic yarn 12 is substituted by yarn change for the relatively light inelastic yarn 2. This yarn 12 will, as before indicated, be of a weight such as would normally be employed for the gage and type of fabric knitted. Now the remainder of the stocking top or garter portion of that top may be knitted as illustrated herein or may be formed in any other desired manner. Herein the said continuing fabric is preferably of a type as shown in United States Patent #2,131,720, but may involve knitting of elastic yarn with inelastic yarn, inlaying

of the elastic or incorporating it in any other desired way.

It is not essential that the elastic yarn be incorporated to be held as by knitting or inlaying at alternate wales 3, 5, 7, etc. Wales more widely spaced may be selected and likewise, the elastic may skip wales as by jumping the elastic yarn feeding finger, or by using a plurality of feeds for inelastic yarn and a single feed for elastic yarn. In the event the elastic yarn is to be inlaid, it will then be held in the tuck wales, that produces a distinctly different edge, but the employment of lighter inelastic yarn at such an edge will correspondingly allow the fabric to be drawn in or of smaller diameter at the edge so that the resulting top will appear very much as illustrated in Fig. 2. In Fig. 2 a stocking top is generally indicated at 13 while part of the leg is shown at 14. The edge 15 shown drawn in or contracted would involve knitting, as in Fig. 1, throughout the courses in which lighter yarn 2 is employed.

Instead of changing yarn and feeding a yarn 12 which is of greater weight than yarn 2, yarn 2 may continue to be fed throughout the entire top and a second yarn will be inserted to feed with it, the weight of both yarns then corresponding to that of the single yarn 12. This avoids a yarn change, but does necessitate mechanism for introducing the second yarn to feed with the light yarn 2.

Mechanism for knitting the fabric herein described is preferably of the type used in circular, independent needle knitting machines although the invention may be applied to other types such as the full fashioned hosiery knitters. The yarn 2 is to be fed at a main yarn feeding station and ordinarily, elastic yarn 1 will be fed at a separate feeding station which would also include means for selecting needles which were to take that elastic yarn and for drawing them down to form the independently knitted stitches thereof. Some mechanism is generally referred to and described in United States Patent #2,131,720 and others, so that it is not deemed advisable to describe it in detail at this time. Similarly, mechanism is now well-known for inlaying and for knitting elastic in conjunction with non-elastic yarn so that if the invention is to be practiced according to either of those schemes of incorporating elastic, those skilled in the art would readily understand the machine construction required.

While tucking at certain wales has been known heretofore and rolling or curling at the edge of the fabric is prevented to a great extent in that way, it has been found that tucking in combination with feeding a finer or lighter inelastic yarn at the edge serves to prevent curling or rolling more effectively. The extent to which the fabric may be drawn in at the edge is controllable for varying the size of inelastic yarn in the first few courses. Drawing the fabric inwardly by feeding a lighter yarn at the edge without tucking is also conducive of good results and a certain amount of curling or rolling may be prevented in that way. For some materials and certain gages of fabric that may prove sufficient. However, much more resistance is built up by employment of both expedients in combination, especially in the longer half hose in which the top of the stocking is generally worn at the most tapered portion of the leg.

The invention applies to all types of material and to all types of hosiery. The proportionate

size of yarn 2 as compared with yarn 12 may vary for different gages of machine or fabric, but the actual size of the yarn 2 as compared to yarn 12 will merely be determined by selecting a yarn light enough in comparison with the yarn 12 so that suitable contraction at the edge of the fabric is realized. Certain variations may be resorted to without departing from the teaching co-extensive with the original concept. The invention is defined in the appended claims.

I claim:

1. A knitted fabric comprising elastic and inelastic yarns, said elastic yarn being knitted under tension so as to contract and draw the fabric together laterally, inelastic yarn at and adjacent the edge of the fabric being lighter than continuing inelastic yarn whereby the fabric may be drawn together to a greater extent at the edge than in following courses.

2. A knitted fabric comprising elastic and inelastic yarns knitted in consecutive courses so that the said elastic yarn will cooperate to form a selvage and will also draw the fabric together laterally upon contraction, said inelastic yarn being knitted in spaced wales and tucked at intermediate wales and being of lesser weight at and adjacent the selvage than in following courses.

3. A knitted fabric comprising stitches of elastic and inelastic yarns, said elastic yarn being knitted under tension and at spaced wales and floated over intervening wales, said inelastic yarn being knitted at spaced wales, tucked at intermediate wales and further being of less weight for a plurality of courses at and adjacent the edge of the fabric than in following courses.

4. A knitted stocking top having elastic and inelastic yarns so incorporated that said elastic yarn is knitted at spaced wales and drawn into tuck stitches at intermediate wales while the elastic yarn is so incorporated as to be held at the spaced wales and floated over intermediate or tuck wales, said elastic being knitted under tension sufficient to draw the said spaced wales together laterally while the fabric is further allowed to be drawn together more at and adjacent the selvage since inelastic yarn at and adjacent the edge is of relatively less weight than inelastic yarn substituted therefor throughout a continuing part of the fabric.

5. A knitted stocking top formed from elastic and inelastic yarns, said elastic yarn being incorporated under tension and to be held at spaced, that is, non-adjacent wales, several courses of inelastic yarn at and adjacent the beginning edge of the top being knitted from an inelastic yarn lighter than would normally be used for the gage of the particular fabric and thereafter having a plurality of courses continuing with inelastic yarn of a normal size for that gage.

6. A knitted stocking top comprising a plurality of courses of which the first course forms a selvage, elastic yarn incorporated under tension and contracted to draw the wales in which it is incorporated to be held laterally toward each other, inelastic yarn knitted at spaced wales and tucked at intermediate wales throughout a plurality of courses after which said inelastic yarn is supplemented by a second inelastic yarn, the size of the first mentioned yarn being substantially less than would normally be used for the particular gage fabric while the second mentioned inelastic yarn in addition to the first will combine to a weight substantially that which

would normally be employed for the particular gage fabric being knitted.

7. In a knitted fabric having courses of elastic and inelastic yarn wherein the elastic yarn is incorporated to be held at spaced wales and under tension so as to contract and draw those spaced wales laterally together, courses of the fabric at and adjacent the selvage thereof being knitted from inelastic yarn of relatively light weight while continuing courses of inelastic yarn are substantially heavier than that inelastic yarn employed in said first courses.

8. A knitted fabric comprising courses of inelastic yarn and elastic yarn knitted to be held at spaced wales and under tension so as to draw those spaced wales laterally together, said elastic and inelastic yarns forming a selvage at the beginning edge of the fabric and the said inelastic yarn for a few courses at and adjacent the selvage being of a weight substantially less than continuing inelastic yarn throughout following 10 courses of the fabric.

OSCAR FREGEOLLE.
